UNITED STATES PATENT OFFICE.

GEORGE H. TABER, OF BINGHAMTON, NEW YORK, ASSIGNOR TO EMCO MANUFACTURING COMPANY, INC., OF BINGHAMTON, NEW YORK, A CORPORATION OF NEW YORK.

MUFFLER.

1,353,863.

Specification of Letters Patent. Patented Sept. 28, 1920.

Application filed December 18, 1919. Serial No. 345,700.

To all whom it may concern:

Be it known that I, GEORGE H. TABER, a citizen of the United States of America, and a resident of Binghamton, in the county of 5 Broome and State of New York, have invented certain new and useful Improvements in Mufflers, of which the following is a specification.

This invention relates to improvements in 10 mufflers for gas engines, etc., and the object of the invention is to provide an extremely simple form of muffler containing in its preferable embodiment, two main parts secured together on longitudinal lines 15 and having clamped between them the baffle plates usually employed for muffling the sound and absorbing the explosions.

With this object in view, my invention consists in the arrangement and combination 20 of parts hereinafter described and then definitely claimed.

In the drawings accompanying and forming part hereof:

Figure 1 is a perspective view of my 25 muffler.

Fig. 2 is a longitudinal central section of the same.

Fig. 3 is a cross section through the line 3—3 of Fig. 2.

30 Fig. 4 is a cross section through the line 4—4 of Fig. 2.

Referring now to the details of the drawings by numerals: My muffler comprises two main parts 1 and 2, each of which may be 35 a casting and one a substantial counterpart of the other. In the most desirable form of my invention, the castings 1 and 2 are provided with interior bosses 5 and 6 which project toward and meet each other, a 40 fillister screw 7 being employed to firmly secure the parts together, as illustrated in Fig. 3, a lock washer 9 being employed under the head of said screw 7. The castings 1 and 2 may also be provided with ears 45 8 and 10, bolts 12 and 14 being employed to firmly secure these ears together, lock washers 13 being employed to hold the nuts on said bolts. The inlet end of the muffler is provided with two reduced portions 16 and 50 18 between which the exhaust pipe from the engine is clamped when the aforesaid bolts 12 and 14 are screwed home. The exhaust end of the muffler is also provided with two

similarly reduced end portions 20 and 22 between which may be similarly clamped 55 the short pipe 24 at the rear end of the muffler, as said parts 20 and 22 are secured together by said fillister screw 7. The interior of the castings 1 and 2 contains baffle plates 26, 28 and 30 of any desirable number, 60 three being illustrated in Fig. 2. These baffle plates may be provided with the usual openings in staggered relation with each other commonly found in baffle plates of mufflers. The interior surfaces of the castings 1 and 2 are provided with ribs 33 and 34 leaving grooves between them and also with lugs 36 and 38, the ribs being preferably on the sides and the lugs on the top and bottom. 70

I desire to call particular attention to these ribs and lugs. They are somewhat of saw-teeth shape and are purposely so cast that the grooves in them are slightly less in diameter than the interior diameter of the 75 castings. In other words, the bottom of the groove in said saw-tooth ribs and lugs is not flush with the inside contour of the castings, but is about an eighth of an inch above the same. This serves two purposes as follows: 80 first, it provides slight spaces between the disks and the inside contour of the castings, between the ribs and lugs, to allow a certain percentage of the gases to pass therethrough, and, second, the disks are caused to buckle 85 slightly thus having a spring to keep the disks tight.

The construction of my muffler is so simple that it is believed no description of its operation is necessary except to state that 90 the gases from the engine as they enter the muffler strike first against the first baffle plate, and then are broken up, part passing through the openings thereof and part passing through the slight spaces between the 95 edges of the baffle and the interior wall of the castings, and then the gases meet the second baffle and, after being again broken up, strike the third baffle, and after passing this, the gases meet the interior lugs 5 and 6, which divide the interior of the muffler, and deflect the gases so as to compel them to divide and pass around said lugs 5 and 6, thus still further reducing the sound, before the gases finally pass out of the discharge of 100 the muffler. 105

I desire to call attention to the fact that my muffler consists of two main parts as 1 and 2 preferably secured together by three bolts or screws and so constructed and fitted together that as the longitudinally split parts 1 and 2 are screwed firmly together the baffle plates 26, 28 and 30 are at the same time firmly secured in position in the grooves between the longitudinal ribs 33 and 34 and the lugs 36 and 38. The same screws also serve to clamp the inlet and exhaust pipes within the longitudinally split muffler.

It will be obvious that modifications and changes may be made without departing from the spirit of my invention, the scope of which is set forth by the appended claims.

What I claim as my invention is:

1. In a muffler, the combination of a casing consisting of two main parts joined on a longitudinal line, each part having lugs on the interior wall thereof, and baffle plates secured between said lugs as the two parts of the casing are secured together, said baffle plates having a space between them and the interior walls of the casing for the passage of the gases, substantially as described.

2. In a muffler, the combination of a casing consisting of two main parts joined on a longitudinal line, each part having ribs and lugs on the interior wall thereof, and baffle plates secured between said ribs and lugs as the two parts of the casing are secured together, said baffle plates having a space between them and the interior walls of the casing for the passage of the gases, substantially as described.

3. In a muffler, the combination of a casing consisting of two main parts joined on a longitudinal line, each part having lugs on the interior wall thereof, and baffle plates secured between said lugs as the two parts of the casing are secured together, said baffle plates being "buckled" by said lugs as they are clamped in position as the two parts of the muffler are secured together, substantially as described.

4. In a muffler, the combination of a casing consisting of two castings joined on a longitudinal line, each casting having a reduced part at each end thereof, lugs cast on the interior of said castings, and baffle plates held in position within the castings by said lugs, the two parts of the casting being se-

cured together and thereby holding the baffle plates in position, substantially as described. 55

5. In a muffler, the combination of a casing consisting of two castings joined on a longitudinal line, each casting having a reduced part at each end thereof, lugs cast on the interior of said castings, baffle plates 60 held in position within the castings by said lugs, a lug projecting from the interior of each casting, and a screw passing through one of said lugs and threaded into the other thereby securing the two parts of the casting 65 together and holding the baffle plates in position, substantially as described.

6. In a muffler, the combination of a casing consisting of two castings joined on a longitudinal line, each casting having a reduced part at each end thereof, the two reduced parts at each end of the casing forming a means of connecting to the exhaust of the engine and to the tail pipe, lugs cast on the interior of said castings, baffle plates 75 held in position within the castings by said lugs, and screws for securing the two parts of said casing together thereby holding the baffle plates in position and securing the exhaust pipe and tail pipe within the reduced 80 parts of the castings, substantially as described.

7. In a muffler, the combination of a casing consisting of two main castings joined on a longitudinal line, each casting having 85 lugs on the interior wall thereof, baffle plates secured between said lugs as the two parts of the casing are secured together, said baffle plates having a space between them and the interior walls of the casing for the passage 90 of the gases, lugs projecting from each casting, and a screw passing through one of said lugs and threaded into the other thereby securing the two castings together and holding the baffle plates in position; the said lugs 95 being located between the last baffle plate and the discharge of the muffler whereby it aids in muffling the explosions, substantially as described.

In testimony whereof I affix my signature 100 in presence of two witnesses.

GEORGE H. TABER.
